CONTROL FOR PLUNGER LIFTS

Howard C. Tait, Pittsburgh, Pa., assignor to The National Supply Company, Pittsburgh, Pa., a corporation of Pennsylvania

Application May 22, 1952, Serial No. 289,277

5 Claims. (Cl. 103—52)

1

This invention relates to plunger lift apparatus and is particularly directed to improvements over devices of the type shown in the copending application of Donald G. Knox, Serial No. 106,579, filed July 25, 1949, for "Plunger Lift."

The principal object of this invention is to provide a simplified control system for regulating the action of the plunger which travels the full length of the eduction tube in the well.

An important object of this invention is to provide improved means for closing the main valve in the well fluid delivery pipe leading from the well head, when the plunger reaches the upper end of its stroke.

Other and more detailed objects and advantages will appear hereinafter.

In the drawings:

Figure 1 is a view in diagrammatic form, partly in section, showing a preferred embodiment of my invention. The parts are shown in the position they assume when the plunger is at the upper end of its stroke, with the main control valve in the act of closing.

Figure 2 is a view similar to Figure 1 showing the parts in the position they assume when the plunger is rising in the eduction tubing.

Figure 3 is a sectional elevation of the control valve assembly which is positioned in the well fluid discharge pipe.

Figure 4 is a side elevation, partly in section, showing the plunger which travels the full length of the eduction tubing.

Referring to the drawings, the well head generally designated 10 is mounted at the upper end of the casing 11. The eduction tubing 12 extends through the head 10 and is connected to the body of the shut-off valve 13. A passageway in the valve 13 establishes communication from the eduction tubing 12 to the stack nipple 14. A bumper spring housing 15 is mounted at the upper end of the stack nipple and is provided with a removable cap 16. The well fluid delivery conduit generally designated 17 includes the shut-off valve 18 and the nipple 19 which connects to a side outlet in the bumper spring housing 15. The main control valve 20 is mounted in the well fluid delivery conduit 17 downstream from the shut-off 18. When this valve 20 is closed the well is "shut in." The valve 20 includes a vertically movable valve stem 21 which is moved by means of a diaphragm 22 acting against the action of a coil spring 23. When pressure is applied to the space 24 above the diaphragm 22 the stem 21 is lowered to open the valve, and when the pressure is vented from the space 24 the coil spring 23 acts to raise the stem 21 and close the valve.

2

A lateral outlet 25 on the well head is connected by means of a nipple 26 to the shut-off valve 27. Gas under pressure is injected into the pipe 28 and passes through the valve 27 and nipple 26 into the interior of the casing 11.

In the general scheme of operation the control valve 20 remains closed while the plunger 29 is at the lower end of the eduction tube 12. During this period the well fluid enters the eduction tube 10 above the plunger, and casing pressure builds up as the gas is injected through the pipe 28. When the pressure reaches a predetermined magnitude the valve 20 is opened. This action serves to reduce the pressure of the gas in the eduction tube above the plunger 29. The plunger is then moved upward through the eduction tube, lifted by the pressure of the gas in the casing which continues to enter the lower end of the eduction tube as the plunger rises. A load of well fluid 15 above the plunger is carried to the surface and is discharged through the pipe 17 and the valve 20. When the plunger 29 enters the stack nipple 14 the valve 20 closes, again "shutting in" the well. The plunger 29 drops down through 20 the eduction tube 12 to the lower end thereof and the cycle is repeated.

In order to carry out this cycle of operations I provide an improved control mechanism which causes the control valve 20 to open when the casing pressure builds up to a predetermined magnitude, and which causes the valve 20 to close when the plunger 29 comes to rest within the stack nipple 14. In accordance with my invention I provide a trigger 30 which is pivoted on the stack nipple at 31 and which extends through a 25 port 32 in the side wall of the stack nipple 14. A movable arm 33 connected to the trigger 30 actuates a vent valve 34. When the plunger 29 is not in the stack nipple 14, the spring 35 moves the trigger 30 and arm 33 to the position shown 30 in Figure 2. In this position the vent valve 34 is closed. When the plunger 29 enters the stack nipple 14 it contacts the trigger 30 and swings it to the position shown in Figure 1, thereby opening the vent valve 34 to bleed the pressure in the 35 line 36.

The control instrument generally designated 37 comprises a casing having a number of parts of the control mechanism positioned therein. Among these parts are the pilot valve 38, the relay valve 39, the bellows assembly 40, the Bourdon tube 41, and the valve assembly 42. Pilot supply gas at relatively low pressure, for example, 20 p. s. i., is supplied through conduit 43 to the terminal 44 of the relay valve 39 and to the 50 terminal 45 of the pilot valve 38. This pilot sup-

ply gas may be obtained from any convenient source, and as shown in the drawings is obtained through a pressure reducing regulator 46 connected to the gas supply pipe 28. The line 47 is connected to the supply pipe 28 at a point near the entrance to the casing 11, and hence reflects the pressure within the casing 11. This line 47 is connected to the Bourdon tube 41. The control line 48 communicates with the space 24 above the diaphragm 22 of the control valve 20, and this line 48 connects to the terminal 49 of the pilot valve 38 and to the terminal 50 of the bellows assembly 40. The trigger line 36 connects to the valve assembly 42 and also to the terminals 51 and 54 of the relay valve 39. The terminal 52 on the pilot valve 38 connects through line 55 with the terminal 53 on the relay valve 39.

The spring 35 normally acts to hold the vent valve 34 against the seat 56 and thereby prevent escape of pressure fluid from the line 36. The stem 57 of the valve 34 projects through seal ring 58 into the chamber 59 which is sealed with respect to the interior of the eduction tube 12. When the plunger 29 reaches the upper end of its travel and enters the stack nipple 14, it contacts the trigger arm 30 and causes the arm 33 to engage the lower end of the valve stem 57, and lift the valve 34 away from its seat 56. The pressure in the line 36 then vents to atmosphere through vent port 60.

The relay valve shown diagrammatically at 39 employs a ball 61 which may engage either an upward facing seat 62 or a downward facing seat 63. When the ball 61 rests by gravity upon the seat 62 it closes off the vent port 64. A diaphragm 65 operates a plunger 66 which may engage the ball 61 and move it upward away from seat 62 and into contact with seat 63. Pressure fluid admitted through terminal 54 operates the diaphragm 65. A restriction 68, located for convenience within the relay valve 39, connects terminals 44 and 51 and hence establishes communication between the pressure fluid supply line 43 and the trigger line 36.

The pilot valve shown diagrammatically at 38 is provided with a valve spool 69 which moves axially within a cylindrical bore 70. An annular groove 71 in the spool 69 connects the terminal 49 with either the terminal 45 or the vent port 72, depending upon the axial position of the spool 69. A compression spring 73 acts resiliently to move the spool 69 in one direction, and such movement is resisted by fluid pressure in the chamber 74 below the spool 69.

The Bourdon tube 41 has its moving end connected to the crank arm 75 of the flapper valve 76, pivotally mounted at 77. A nozzle 78 engages the under side of the flapper valve 76 to form a seal. The nozzle 78 is also movably mounted, and as shown diagrammatically in the drawings, the nozzle is carried on an arm 79 pivotally supported at 80. A link 81 is pivoted at one end to the arm 79 and at the other end to the post 82 fixed on the end wall of the bellows 40. When the pressure in the bellows chamber 83 increases, the nozzle 78 is moved toward the flapper valve 76. One or more loops 84 in the nozzle feed pipe 85 permit the nozzle 78 to move freely through its relatively short arc of movement. When pressure in the Bourdon tube increases, the flapper valve 76 is swung toward the nozzle 78. The nozzle 78 and flapper valve 76 are collectively referred to as the vent valve 42.

In the position of the parts as shown in Fig-

ure 1, the plunger 29 is in the stack nipple 14 and the vent valve 34 is open. The trigger line 36 is therefore vented to atmosphere through vent port 60. If desired, a dash-pot mechanism, not shown, can be employed to prevent too rapid closing of the vent valve 34 in the event that the plunger 29 should descent out of contact with the trigger 30 before any considerable pressure drop occurs in pipe 36. The release in pressure below the diaphragm 65 in the relay valve 39 allows the sliding plunger 66 to drop, and the ball 61 rests on seat 62, closing off vent port 64. Pressure from the pilot supply line 43 then passes into the relay valve 39 through terminal 44, out through terminal 53, through pipe 55, and into the chamber 74 in the pilot valve 38 through terminal 52. The spool 69 moves up against the action of the spring 73 to close off terminal 45 and to connect the terminal 49 with the vent port 72. The control pipe 48 is thus vented to atmosphere, and the reduction in pressure in the space 24 above the diaphragm 22 in the motor valve assembly 20 permits the spring 23 to lift the stem 21 to close the valve heads 8 against the valve seats 9 (see Figure 3).

Venting of the control pipe 48 through vent port 72 in the pilot valve 38 serves to effect closing of the control valve 20, as set forth above, and also acts to decrease the pressure in the bellows chamber 83. This allows the arm 79 to swing about its pivot 80 and move the nozzle 78 away from the flapper valve 76. The nozzle 78 then vents the line 85 and trigger pipe 36 to atmosphere even though pressure fluid is being constantly supplied through restriction 68 from the pilot supply pipe 43. A reduction in casing pressure is occasioned by passage of gas through the control valve 20 during its open period. This reduction in pressure is reflected by action of the Bourdon tube in lifting the flapper valve 76 away from the nozzle 78. The plunger 29 drops back through the eduction tube 12 to the lower end thereof in the well. The control valve 20 remains closed, with the well "shut in."

The plunger 29 remains at the lower end of the eduction tube 12 in the well until the casing pressure builds up to a predetermined value. The increase in casing pressure is brought about either by entry of formation gas into the casing 11 at the lower end thereof or by admitting gas under pressure through pipe 28, or both. When the pressure in the casing 11 builds up to a predetermined intensity the Bourdon tube 41 lowers the flapper valve 76 into contact with the nozzle 78, to close off the nozzle 78 and substantially prevent escape of pressure fluid therefrom.

Pressure fluid supplied through restriction 68 then builds up pressure in the line 85 and trigger pipe 36. The diaphragm 65 in the relay valve 39 is raised, causing the plunger 66 to seat the ball 61 against the seat 63. This action vents line 55 through port 64 and allows the spring 73 in the pilot valve 38 to shift the spool 69 to a position to close off the vent port 72 and to connect terminal 45 with terminal 49. Pressure fluid then passes from the pilot supply line 43 into the control pipe 48, and into the bellows chamber 83. The various parts of the device are now in the position shown in Figure 2.

When the pressure in the control pipe 48 builds up sufficiently it acts on the diaphragm 22 to overcome the force of the spring 23 and open the control valve 20. The gas under pressure in the eduction tube 12 then passes out through the

discharge pipe 17. The consequent reduction in pressure in the eduction tube 12 above the plunger 29 causes the plunger to be driven to the surface by pressure fluid from the casing 11. A slug of well fluid is lifted by the plunger 29, and this well fluid passes out through discharge pipe 17 and control valve 20 before the plunger 29 reaches the stack nipple 14. When the plunger 29 reaches the stack nipple 14 it engages the trigger 30 and opens the vent valve 34, and the cycle repeats. A valve 29a in the plunger 29 opens and the plunger drops back down the eduction tube 12 into the well.

Having fully described my invention, it is to be understood that I do not wish to be limited to the details herein set forth, but my invention is of the full scope of the appended claims.

I claim:

1. In a plunger lift device having a valved plunger adapted to travel freely under pressure substantially the full length of an eduction tube in a well, the combination of: a well head assembly connected to the upper end of the eduction tube, a discharge pipe leading from the well head assembly, a control valve for controlling flow of well fluid through the discharge pipe, resilient means for closing the control valve, power means for opening the control valve against the action of the resilient means, a trigger element movably mounted on the well head assembly to be actuated when the plunger reaches the upper end of its travel, a vent valve mounted on the well head assembly, a pipe connected to said vent valve, means whereby the trigger element may open the vent valve to vent the pipe, a supply pipe for supplying pressure fluid to said control pipe, and means operable to deenergize said power means to permit the resilient means to close the control valve upon opening of the vent valve by the trigger element.

2. In a plunger lift device having a valved plunger adapted to travel freely under pressure substantially the full length of an eduction tube in a well, the combination of: a well head assembly connected to the upper end of the eduction tube, a discharge pipe leading from the well head assembly, a control valve for controlling flow of well fluid through the discharge pipe, resilient means for closing the control valve, pressure operated means for opening the control valve against the action of the resilient means, a control pipe connected to said pressure operated means, a trigger element movably mounted on the well head assembly to be actuated when the plunger reaches the upper end of its travel, a vent valve mounted on the well head assembly, a second pipe connected to said vent valve, means whereby the trigger element may open the vent valve to vent the second pipe, a supply pipe for supplying pressure fluid to said control pipe and to said second pipe, and means operable to vent the control pipe when said vent valve vents said second pipe to permit the resilient means to close the control valve.

3. In a plunger lift device having a valved plunger adapted to travel freely under pressure substantially the full length of an eduction tube in a well, the combination of: a well head assembly connected to the upper end of the eduction tube, a discharge pipe leading from the well head assembly, a normally closed control valve interposed in the discharge pipe, pressure operated means for opening the control valve, a con-

trol pipe connected to said pressure operated means, a trigger element movably mounted on the well head assembly to be actuated when the plunger reaches the upper end of its travel, a vent valve mounted on the well head assembly, a second pipe connected to said vent valve, resilient means for closing the vent valve, means whereby the trigger element may open the vent valve against the action of said resilient means to vent the second pipe, a supply pipe for supplying pressure fluid to said control pipe and to said second pipe, and means operable to deenergize the pressure operated means upon opening of the vent valve by the trigger element to permit the resilient means to close the control valve.

4. In a plunger lift device, the combination of: a well casing, an eduction tube therein, a valved plunger adapted to travel freely under pressure substantially the full length of the eduction tube, a well head assembly connected to the upper end of the casing and eduction tube, a discharge pipe leading from the well head assembly, a control valve for controlling flow of well fluid through the discharge pipe, resilient means for closing the control valve, pressure operated means for opening the control valve against the action of the resilient means, a control pipe connected to said pressure operated means, a trigger element movably mounted on the well head assembly, a second pipe connected to said vent valve, resilient means for closing the vent valve, means whereby the trigger element may open the vent valve against the action of said resilient means to vent the second pipe, a supply pipe for supplying pressure fluid to said control pipe and to said second pipe, a second vent valve connected to said second pipe, a Bourdon tube connected to open said second vent valve upon increase in pressure therein, means establishing communication between the interior of the casing and said Bourdon tube whereby the second vent valve is closed upon increase in casing pressure beyond a predetermined intensity, and means operable to vent the control pipe to permit the resilient means to close the control valve upon opening of the vent valve by the trigger element.

5. In a plunger lift device having a valved plunger adapted to travel freely under pressure substantially the full length of an eduction tube in a well, the combination of: a well head assembly connected to the upper end of the eduction tube, a discharge pipe leading from the well head assembly, a control valve for controlling flow of well fluid through the discharge pipe, resilient means for closing the control valve, pressure operated means for opening the control valve against the action of the resilient means, a control pipe connected to said pressure operated means, a trigger element movably mounted on the well head assembly and actuated by the plunger at the upper end of its travel, a vent valve mounted on the well head assembly, a second pipe connected to said vent valve, resilient means for closing the vent valve, means whereby the trigger element may open the vent valve against the action of said resilient means to vent the second pipe, a supply pipe for supplying pressure fluid to said control pipe and to said second pipe, and means operable upon venting of the second pipe to vent the control pipe and permit the resilient means to close the control valve.

HOWARD C. TAIT.
